UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR CASING OF SODA-WATER APPARATUS.

Specification forming part of Design No. 5,985, dated July 16, 1872.

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

This invention consists in an ornamental design for the casing of a soda-water apparatus to be placed against a wall, the operator standing in front of the apparatus.

In the photograph, A represents the lower portion of the casing of a soda-water apparatus, which is of rectangular form. B is the upper portion of the casing, the front of which slopes or inclines inward and upward from a to b, while the sides incline inward and upward from c to d. Above the portion B is a shelf or platform, C, which is surmounted by an ornamental railing, D, above which rises the upper portion of the back E, which rises vertically

from the bottom of the casing and is intended to be placed against the wall of the apartment, the operator standing in front of the apparatus and between it and the counter. At the center of the front of the portion A is a projecting portion, G, which is surmounted by a semicircular or arched portion, H, containing a tablet or medallion with the representation of an iceberg thereon, the design thus produced being unique and ornamental.

Claim.

What I claim as my invention, and desire to secure by Letters Patent, is—

The design for the casing of a soda-water apparatus, substantially as herein shown and described.

Witness my hand this 6th day of May, A. D. 1872.

GEO. F. MEACHAM.

In presence of—

P. E. TESCHEMACHER,
G. A. MEACHAM.
